Application October 5, 1956, Serial No. 43,244

Term of patent 14 years

(Cl. D92—1)

Fig. 1

Fig. 3

Fig. 1 is a plan view of a puffed textile fabric showing our new design;

Fig. 2 is a sectional view of the fabric along the line 2—2 of Fig. 1, and

Fig. 3 is a sectional view of the fabric along the line 3—3 of Fig. 1.

The design is embodied in a puffed fabric comprising a series of puffs shown in plan in Fig. 1 and in cross-section in Figs. 2 and 3. The puffs are held in the fabric by threads shown as straight lines in Figs. 2 and 3 interlaced in the fabric.

We claim:

The ornamental design for a puffed textile fabric, as shown and described.
